(57) **CLAIM**

The ornamental design for a sling bag with circular pocket, as shown and described.

DESCRIPTION

FIG. 1 is a front elevational view of a sling bag with circular pocket with a carry strap and having a first preselected fabric in at least one of a color and a pattern;

FIG. 2 is a rear elevational view of the bag of FIG. 1 showing a circular pocket in a second preselected fabric which coordinates with the first preselected fabric, and further showing a zipper for accessing the bag;

FIG. 3 is a right side elevational view of the bag of FIG. 1;

FIG. 4 is a top plan view of the bag of FIG. 1;

FIG. 5 is a bottom plan view of the bag of FIG. 1, showing the circular pocket along a rear portion of the sling bag;

FIG. 6 is the rear elevational view of FIG. 2, now showing the circular pocket in a third preselected fabric which is different than the first preselected fabric; and,

FIG. 7 is the rear elevational view of FIG. 2, now showing the circular pocket in a three-quarter open-pocket configuration.

The broken line showing of hardware (e.g., the zippers, buckles, closure, carry strap) as well as the position of the hardware relative to the claimed design and any other broken lines are to show the environment only and are not part of the claimed design.
